Specification for Design.

Patented June 7, 1921.

Application filed December 17, 1920. Serial No. 431,496. Term of patent 14 years.

To all whom it may concern:

Be it known that I, FRANK C. DE REAMER, a citizen of the United States, residing at Schenectady, in the county of Schenectady, State of New York, have invented a new, original, and ornamental Design for a Combined Snap-Switch and Plug-Connector, of which the following is a specification, reference being had to the accompanying drawing, forming part thereof.

The figure is a perspective view of a combined snap switch and plug connector embodying my design.

What I claim is:—

The ornamental design for a combined snap switch and plug connector, as shown.

In witness whereof, I have hereunto set my hand this 16th day of December, 1920.

FRANK C. DE REAMER.
